TOPICAL GERMICIDAL MEDICINE

Frank J. Bickenheuser, Tulsa, Okla., assignor, by direct and mesne assignments, of three-fourths to Gelocide Corporation, Tulsa, Okla., and one-fourth to George Fulton Collins, Sr., Tulsa, Okla.

No Drawing. Application February 4, 1937,
Serial No. 124,135

4 Claims. (Cl. 167—58)

The present invention relates to a topical medicine in the form of a substantially clear oily liquid which preferably is entirely free from odor or which at any event does not have any pronounced characteristic odor. Said oily liquid carries a strong germicidal constituent in solution, and said liquid is entirely suitable for application to mucous surfaces and which when applied to a mucous surface will combine with moisture present thereon or which exudes from such mucous surface, forming a jelly-like mass which will adhere tenaciously to said mucous surface, for a considerable period, and until it has been largely diluted with the watery exudations of such mucous surface, after which the said coating can be readily washed off, for example with warm water.

The following specific formula is given, which has been found to give excellent results, but I desire to call attention to the fact that the invention is not restricted to the said specific example, which is given purely by way of illustration:

25	Oleic acid	6.5 liters
	Triethanolamine	2 liters
	Medicinal mineral oil	5 liters
	Cottonseed or olive oil	3.75 liters
30	Ortho-iodo-benzoic acid	4 ounces av. (equivalent to about 124 grams)

In producing the medicine from the above formula, the following has been found to be the most advantageous procedure. The oleic acid is first heated to about 120° F., and the iodo-benzoic acid is added, and the mixture is stirred until the said iodo-benzoic acid has gone into solution. 15 or 20 minutes stirring will usually be sufficient. This solution is then drawn off into a larger receptacle which is placed in a water bath or oil bath and maintained at about 100° F. The mineral oil is then added and well stirred for 10 to 20 minutes. Then the cottonseed oil or olive oil is added and again stirred for 10 to 20 minutes, the temperature at this time being about 100° F. The triethanolamine is added and well stirred. The temperature rises considerably on account of the reaction taking place between the triethanolamine and the oleic acid, which as well known forms a triethanolamine soap, which is miscible with the oils. The addition of the triethanolamine first gives a milky solution, and upon continuing the stirring for 10 to 20 minutes the mass becomes thoroughly clear. The solution can then be allowed to settle, and the clear oil decanted and is then ready for putting up into packages to sell. A convenient form of packaging is a collapsible metal tube having a screw cap. The completed medicine is a viscous oily mixture, of

a yellowish or amber color, which can be kept for long periods without deterioration.

In the above formula, oleic acid was referred to. It will be understood that for producing a mixture of higher viscosity, a small amount of the oleic acid can be substituted by solid fatty acids such as stearic. I would not ordinarily recommend substituting more than one-fifth of the oleic acid by stearic.

The medicinal mineral oil can be the widely used variety sold as a mild laxative, being a water-white liquid, having a specific gravity of about 0.880, and a Saybolt viscosity at 100° C. about 250, and free from unsaturated constituents. Other similar oils can be used.

The cottonseed oil or olive oil may be the usual well refined edible grades. In place of these oils, other well refined liquid fatty oils can be used, for example soybean oil, peanut oil, sesame oil, perilla oil or the like, all preferably in the well refined condition and substantially free from odors. If the fatty oil used contains considerable free fatty acid, slightly more of the said oil and slightly less of the oleic acid can be suitably employed. The use of the well refined oil and of the well refined free fatty acid are however more desirable, as giving a product more free from odor and which will apparently keep better.

Although the product is of an oily nature, it has a strong affinity for water, and when the said oily material comes into contact with water, (in other words is "hydrophilic") it forms a mass of jelly-like consistency which strongly adheres to wet mucous surfaces.

The action of the oily medicine when it is brought into contact with water (or aqueous liquids including aqueous discharges being given off by mucous surfaces) containing bacteria or other living micro-organisms, has been carefully studied, under the microscope. The oily material bursts into the aqueous liquid forming billows of soft jelly-like consistency, the water acting upon the ortho-iodo-benzoic acid, apparently causing hydrolysis of the latter, giving the appearance of a spray of germicidal material which projects out into the aqueous liquid, immediately rendering inactive the micro-organisms present, and the jelly sucking in these micro-organisms, to completely envelop the same. Following this action, the jelly stiffens somewhat, imprisoning the said micro-organisms, which are thereby destroyed. This action takes place irrespective of what forms of micro-organisms are present, whether *coll-bacillus*, *staphylococci*, *spirochaetae*, *streptococci*, spores, *spermatozoa* or various mixed cultures, or in fact any living organisms.

The medicine is particularly advantageous for application to mucous surfaces from which liquids are being exuded, whether in normal healthy condition or in a diseased condition. It is a par-

ticularly advantageous medicine to apply, for example, in the treatment of various vaginal disorders, such as all forms of leucorrhea, including cervicitis and vaginitis, and as a preventive 5 against gonorrhea.

For this purpose a small quantity, say a tea-spoonful, can be injected into the vaginal cavity with a syringe advantageously on retiring, followed next morning by a douche of lukewarm 10 water.

When so introduced, a jelly-like product will be formed by the union of the oily medicine with the aqueous exudations of such mucous surfaces or other aqueous liquids present, which will ordinarily persist on said surfaces for a considerable period, e. g. 8-10 hours, during all of said period it is active in destroying all living organisms present. No bandages, tampons or the like are needed to hold the medicine in place, since 20 after application, it is converted by action of the aqueous secretions, into a jelly-like mass that adheres to the said surfaces.

The function of the oleic acid and triethanolamine are to combine with each other and form a 25 triethanolamine oleate (a soapy material) which is readily soluble in oils, and in order to subsequently coat with aqueous exudations to form the jelly-like mass referred to above. This triethanolamine oleate in the presence of oil and 30 aqueous fluids produces a soft colloidal mass of such a consistency that it cannot cause irritation of the mucous surfaces. It would be impossible to substitute a soda or potash soap for the triethanolamine oleate, with satisfactory results. 35 The oily medicine, and the jelly-like mass avidly absorb all bacteria and other living organisms in said aqueous secretions, to envelop and imprison the same.

The cottonseed oil or other liquid fatty oil 40 co-acts with the mineral oil to give a jelly which is more firm and adsorbent and clings better to the mucous surfaces. Without the mineral oil present the action of the aqueous liquids would give a product which although somewhat jelly-like would in many cases be too hard and solid, and more or less brittle. The mineral oil gives 45 the jelly a far better consistency, softer and of generally better physical properties, and aids in the more rapid spreading of the medicine and 50 jelly over the mucous surfaces.

A particularly important feature of the present invention is that the material either as originally employed or after conversion into jelly, has no irritating action on the mucous surfaces and 55 causes no irritation or discomfort when so applied, and has no harmful effect on the tissue.

It would not be feasible to apply iodo-benzoic acid to mucous surfaces such as referred to above, by other methods and obviously it would not be 60 feasible to apply this material to the mucous surfaces in such a manner that it would be held in contact therewith for a period of many hours, without the use of bandages, tampons and the like, which are generally objectionable.

65 I claim:—

1. A vehicle for medicines to be applied to mucous surfaces, the same being a substantially clear oily liquid consisting essentially of a normally liquid fatty oil, a well purified normally 70 liquid mineral oil which is substantially non-volatile at room temperature, and the reaction

product of oleic acid and triethanolamine, the oleic acid being several times the volume of the triethanolamine, and the volume of the fatty oil plus the volume of the mineral oil being only slightly over one-half of the total volume of said 5 oily vehicle, such vehicle being a substantially clear oily appearing liquid, which spreads over and which clings readily to mucous surfaces when applied thereto, and which when so applied forms a mass of jelly-like consistency by 10 taking up the aqueous secretions of said mucous surfaces, which jelly-like mass will cling to the said mucous surfaces until excessively diluted.

2. An oily germicidal topical medicine suitable 15 for the treatment of vaginal disorders and for preventing gonorrhea, which consists substantially of iodo-benzoic acid dissolved in a vehicle of oily nature, such vehicle containing as its essential constituents a purified mineral oil and a fatty oil, and the reaction product of triethanolamine and a fatty acid material composed at 20 least in major part of oleic acid, said components being in such proportions as to give a freely liquid oil which upon taking up aqueous fluids containing bacteria, will produce a mass of soft jelly-like consistency which will envelop and retain any bacteria present, which jelly-like mixture will cling tenaciously to said mucous surfaces until 25 excessively diluted and capable of being readily washed off when so diluted.

3. An oily germicidal medicine suitable for the treatment of vaginal disorders and for preventing gonorrhea by injection into the vaginal cavity, which consists essentially of an iodo benzoic acid, dissolved in a vehicle of oily nature, such vehicle containing as its essential constituents a purified mineral oil and a fatty oil and the reaction product of triethanolamine and a fatty acid material composed at least in major part of 30 oleic acid, the amount of the fatty oil plus the amount of the mineral oil being only a minor fraction greater than the amount of the triethanolamine plus the amount of the fatty acid material, and the amount of the fatty acid material being substantially greater than the 35 amount of the triethanolamine, such topical medicine being non-irritating when applied to mucous surfaces, and forming thereupon a jelly-like mixture which clings tenaciously to said mucous surfaces until excessively diluted and being readily 40 washed off when so diluted.

4. A topical germicidal medicine suitable for the treatment of vaginal disorders and for preventing gonorrhea by injection into the vaginal cavity, which consists essentially of purified normally non-volatile liquid mineral oil and a normally liquid fatty oil with the reaction products of triethanolamine and oleic acid, said components being in such proportions as to give a freely 45 liquid oil which upon taking up aqueous fluids containing bacteria, will produce a mass of soft jelly-like consistency which will envelop and retain any bacteria present, and iodo-benzoic acid in solution therein, such medicine being a substantially clear oil, and being non-irritating when 50 injected without previous dilution into the vaginal cavity, and when so applied combining with the moist exudations in the vaginal cavity to form 55 an adherent jelly-like mass having germicidal properties.

70 FRANK J. BICKENHEUSER.
